(57) **CLAIM**

The ornamental design for an oxygen generator, as shown and described.

DESCRIPTION

FIG. 1 is a top, front, right perspective view of an oxygen generator showing my new design;

FIG. 2 is a bottom, rear, left perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines in the drawings depict the portions of the oxygen generator that form no part of the claimed design.
